BRACKET FOR OUTBOARD MOTORS

Casmir I. Olexiewicz, Los Angeles, Calif.
(1445 W. El Segundo Blvd., Compton, Calif.)

Filed Oct. 16, 1959, Ser. No. 57,960

Term of patent 7 years

(Cl. D54—2)

Fig. 1 is a plan view of a bracket for outboard motors, showing my new design.

Fig. 2 is a side elevational view thereof.

Fig. 3 is an end elevational view of the bracket, partially in cross-section along the line 3—3 of Fig. 1.

The side of the bracket not shown is a mirror image of the side shown.

I claim:

The ornamental design for a bracket for outboard motors, substantially as shown and described.
